UNITED STATES PATENT OFFICE

HENRY JOSEPH ROUND, OF MUSWELL HILL, LONDON, AND WILLIAM JAMES PICKEN, OF SOUTHEND-ON-SEA, ENGLAND, ASSIGNORS TO RADIO CORPORATION OF AMERICA, A CORPORATION OF DELAWARE

MEANS FOR SUPPORTING THE ELECTRODES OF THERMIONIC DEVICES

Original application filed February 23, 1922, Serial No. 538,512, and in Great Britain March 31, 1921. Divided and this application filed September 25, 1929. Serial No. 394,949.

In thermionic devices it is desirable that the electrodes should be supported as securely as possible and at the same time it is necessary that they should be effectively insulated from one another.

The object of this invention is to provide improved means for supporting and insulating the electrodes.

According to the novel disclosure in our 10 United States application Serial No. 538,512, filed Feb. 23, 1922, of which application this is a division, an electrode of a thermionic device is supported and insulated by means of a support made of quartz. Preferably the 15 quartz support consists of a stem surrounded for a considerable portion of its length by a cylindrical part which is preferably also constructed of quartz. On to each end of the stem may fit supports or connections of metal.

It often happens that several electrodes are supported on various parts of the glass of which the containing vessel is constructed, the glass in between the points on which the electrodes are supported being used to insulate 25 the electrodes from one another. It has been found that the insulation of the glass between the various electrodes becomes insufficient owing either to the temperature to which the glass is raised or to a metallic deposit 30 upon the inside of the glass or to both circumstances. In order to obviate this difficulty in accordance with the invention disclosed in the present application, a sheet or sheets of mica is or are interposed between the 35 electrode and the glass on which it is supported. In some cases it may be sufficient to employ a single sheet or layer of mica, but it is preferable to employ two adjacent layers having between them a space of considerable 40 length compared to its width, so that no metallic deposit can be formed upon the inner surfaces of the mica.

Our invention is illustrated by the drawing in which

45 Figure 1 shows a valve the electrodes of which are supported by quartz supports;

Figure 2 shows a fragmentary view of a thermionic device having a layer of mica around the stem; and

50 Figure 3 is a modification of Figure 2.

Figure 1 shows a valve comprising a closure member 1 in which the filament 2 and grid 3 are supported on a reentrant glass stem 4 at one end of the closure 1 in a known manner, and the cylindrical anode C is supported 55 at 5 on a reentrant stem 6 at the other end of the closure 1 also in a known manner. In order to retain the anode C correctly spaced in position with respect to the grid 3 the upper end of the anode is provided with supports D (usually three) attached to arms E 60 carried by the supports F for the grid through a supporting frame or ring G. The ring G is in turn carried by the supports F for the grid. Quartz insulators B serve as 65 the connections between the corresponding parts D and E. The ends of D and E are usually made hollow and fit tightly over the stems A of the quartz supports as more clearly shown in the parent application above mentioned. 70

Figure 2 shows part of a valve in which an electrode H is supported from a glass stem I with the interposition of a piece of mica J. It will be understood that the electrode C of 75 Figure 1 may likewise be supported from the glass stem or reentrant portion 6 with the interposition of a piece of mica. The mica J interposed between the electrode and the glass closure increases the insulation between 80 the electrodes of the tube.

Figure 3 is a similar view showing two cylindrical pieces of mica J and K; the piece J is considerably shorter than the piece K so that spaces L are formed at each end between the outer piece K and the glass. In operation metallic radiation from the cathode cannot form a metallic deposit on the inner surface of mica or glass forming the spaces 85 as described above. Thus, the insulation of the electrode supported by pieces J and K is insured. This in turn increases the life and efficiency of the tube. 90

We claim:

1. In a thermionic device, a glass envelope 95 having a reentrant portion, an electrode supporting member mounted upon said reentrant portion, an electrode carried by said member, and an insulator of mica interposed between 100

said supporting member and the reentrant portion.

5 2. In a thermionic device, a glass envelope having a reentrant portion, electrode supporting means comprising a ring member mounted upon said reentrant portion, an electrode carried by said ring member, and a sheet of mica interposed between said reentrant portion and said ring member.

10 3. In a thermionic device, a glass envelope having a reentrant stem, a sheet of mica carried thereby, a second sheet of mica carried by said first named sheet, said second sheet of mica being of greater width than said first 15 sheet, and an electrode carried by said second sheet of mica.

20 4. In a thermionic device, an evacuated envelope having a reentrant stem, electrode supporting means comprising a ring member clamped upon said reentrant stem, an electrode carried by said ring member, and a pair 25 of sheets of insulating material interposed between said reentrant stem and said ring member, the outer sheet of insulating material adjacent the ring member being wider than the inner sheet adjacent the reentrant stem and having a portion at each end which extends beyond the corresponding end of the inner sheet, whereby at each end of the inner 30 sheet there is formed an annular space between each extended portion of the outer sheet and the reentrant stem.
